Primary Examiner — Michelle E. Wilson*Assistant Examiner* — Clese Moore, Jr.(74) *Attorney, Agent, or Firm* — FAEGRE DRINKER BIDDLE & REATH LLP(57) **CLAIM**

The ornamental design for shorts, as shown and described.

DESCRIPTION

FIG. 1 is a perspective view of a pair of shorts showing our new design;

FIG. 2 is a front elevational view thereof;

FIG. 3 is a rear elevational view thereof;

FIG. 4 is a right side elevational view, the left side elevational view being a mirror image thereof; and,

FIG. 5 is a front elevational view of the present invention with a portion of the front of the shorts cut away and a portion of inner layer of the back cut away.

The broken lines in the drawings are for the purpose of illustrating portions of the shorts that form no part of the claimed design.
